(57) **CLAIM**

The ornamental design for a cylindrical dispensing organizer, as shown and described.

DESCRIPTION

FIG. 1 depicts a perspective view of the dispensing organizer in an essentially screwcap-off, compartments-closed state.

FIG. 2 depicts a top plan view thereof.

FIG. 3 depicts a bottom plan view thereof.

FIG. 4 depicts a first side elevation view thereof, including the screwcap.

FIG. 5 depicts an opposite second side elevation view thereof, including the screwcap.

FIG. 6 depicts a perspective view of the dispensing organizer in an essentially screwcap-off, compartments-open state, including the screwcap and lid for cylindrical compartment.

FIG. 7 depicts a top plan view of the organizer of FIG. 6.

FIG. 8 depicts a bottom plan view of the organizer of FIG. 6.

FIG. 9 depicts a first side elevation view of the organizer of FIG. 6, including the screwcap and lid for cylindrical compartment.

FIG. 10 depicts an opposite second side elevation view of the organizer of FIG. 6, including the screwcap and lid for cylindrical compartment; and,

FIG. 11 depicts a perspective view of the dispensing organizer in an essentially screwcap-on state.
